UNITED STATES PATENT OFFICE.

EDLE-KRISTINE THORDARSON, OF AARHUS, DENMARK.

HEEL FOR BOOTS AND SHOES.

Application filed September 11, 1922. Serial No. 587,461.

To all whom it may concern:

Be it known that I, EDLE-KRISTINE THORDARSON, a subject of the King of Denmark, residing at Aarhus, Montanagade 30, Denmark, have invented certain new and useful Improvements in Heels for Boots and Shoes, of which the following is a specification.

The present invention relates to a heel for boots and shoes and consists in that the heel is provided with a plurality of pointed projections in order to prevent slipping. The invention further consists of a plate which is adapted to be arranged on the heel in order to cover the pointed projections.

One way of carrying out the invention consists in the upper side of the heel being made from a metal plate which is surrounded by a leather or rubber edge which forms an elastic tread for the shoe.

The accompanying drawing shows several ways of carrying out the invention in which:

Figure 1 is a vertical section showing the pointed projections and the edge,

Fig. 2 is a bottom view of the heel with the plate in place,

Fig. 3 is a bottom view of the heel showing the plate removed,

Fig. 4 is a vertical section taken at right angles to the length of the heel, and

Fig. 5 is a vertical section of a modified form.

The heel consists of a metal plate *a* and surrounding edge *b* of leather, rubber or the like. On the plate *a* and inside of the edge *b* are arranged a plurality of pointed projections *c* the length of which correspond to the height of the edge *b*.

The plate *a* is provided with a channel slot *d* in which a spring extension of the plate *f*, may be inserted. The plate *f* when thus inserted in place is adapted to rest on the edge *b* and consequently cover the projections.

When the plate *f*, which is maintained in place by means of the extension *e*, is removed by pulling the extension out of the slot *d*, the projections *c* will be uncovered, and consequently when the heel is on the ground the edge *b* will be slightly compressed, thus allowing the pointed projections to contact with the ground in order to prevent slipping.

By replacing the plate *f* on the heel the pointed projections will be covered and, therefore, will not injure the surface with which the heel comes in contact.

The plate *f* is provided with a hole *g* by means of which the plate can be removed from the heel or inserted in place by any suitable means.

The plate *a* is shown as covered by a layer of rubber *i*, or any other suitable material which may be integral with or separate from the edge *b*. The edge and layer *i* are provided with corresponding holes *j* by means of which the heel may be fastened to the shoe.

The edge *b* may have any suitable shape, and the projections *c* may constitute pins or pointed heads which may be screwed or otherwise secured to the plate.

According to the modification shown in Fig. 5, the edge *b* is omitted, and the plate *a* is secured to the shoe by means of a screw *l* which is screwed into the heel *m*. The cover plate *f* is made in this case only so large that it just covers the projections *c* on the plate *a*.

Having now particularly described and ascertained the nature of my said invention and in what manner the same is to be performed, I declare that what I claim is:

1. A heel for boots and shoes comprising a metal plate having pointed projections thereon and a channel slot therein; and a cover plate having a spring extension thereon adapted to be removably inserted in said slot of the metal plate to thus cover the pointed projections.

2. A heel for boots and shoes comprising a metal plate having pointed projections thereon; an edge extension on said plate; and a cover plate removably secured to said metal plate and adapted to seat on said edge extension to cover said projections.

3. A heel for boots and shoes comprising a metal plate having pointed projections thereon and a channel slot therein; an edge extension on said plate; and a cover plate having a spring extension thereon adapted to be removably inserted in said slot of the metal plate to thus seat on said extension and to cover the pointed projections.

4. A heel for boots and shoes comprising a metal plate having pointed projections thereon; an edge extension on said plate and around said projections; and a cover plate secured to said plate adapted to seat on said extension and cover said projections.

In testimony whereof I affix my signature.

EDLE-KRISTINE THORDARSON.
